TEXTILE ARTICLE TREATING APPARATUS

Christian F. Meyer, Wyomissing, Pa., assignor to
 Textile Machine Works, Wyomissing, Pa., a
 corporation of Pennsylvania

Application January 30, 1941, Serial No. 376,662

22 Claims. (Cl. 68—6)

My invention relates to means for processing textile fabrics composed of synthetic linear condensation polyamide yarns or other yarns whose reactions to processing treatments are similar to those of polyamide yarns, and more particularly to means for permanently fixing the yarn formation of such textile fabrics prior to subjecting them to any other processing treatment.

In treating textile articles composed of polyamide yarns it has been found that when the same steps are followed as are employed in treating silk articles, certain operations such as hot scouring, dyeing and rinsing, produce wrinkles and other irregularities in the fabric and in the loop formation thereof which are difficult to remove by subsequent treating operations.

It has been proposed, in accordance with U. S. Patent No. 2,157,119 to J. B. Miles, Jr., dated May 9, 1939, to overcome the aforesaid difficulties by subjecting polyamide yarn fabrics to a setting treatment, prior to the scouring, dyeing and other treatments to which the fabrics are subsequently subjected. However, no satisfactory equipment has heretofore been provided for such purpose.

It is an object of my invention to provide novel means for permanently fixing the yarn formation of polyamide yarn articles.

It is another object of my invention to provide novel means for effecting processing treatments such as disclosed by the aforesaid patent.

It is a further object of my invention to provide novel means for permanently fixing the yarn formation of textile fabrics composed of polyamide yarns or other yarns having like reactions to processing treatments, prior to subjecting such fabrics to any other processing treatment.

Another object is to provide novel means which may be utilized in connection with the manufacture of stockings made entirely or partially of polyamide yarns, for effecting fixation or setting of the shape of the loops and the shape of the stocking prior to subjecting the article to certain standard manufacturing steps.

Another object is to provide a chamber by means of which an article may be subjected or exposed to a processing medium under conditions of heat and moisture not reached in subsequent processing steps, whereby articles composed entirely or partially of polyamide yarns may have their yarn arrangement permanently set.

Among other objects of the invention are to provide textile treating apparatus having in combination one or more novel devices such as a

heating chamber; automatic means for opening and closing the door of the heating chamber; automatic means for locking and unlocking the door of the treating chamber; automatic means for turning on and off the heating medium; a timer, the starting of which is controlled by the pressure in the treating chamber; automatic means for limiting the time of treatment; and means controlled by the pressure in the treating chamber for controlling the automatic operation of the door locking and unlocking means.

With these and other objects in view, which will appear as the description proceeds, my invention resides in the novel elements, features of construction and arrangement of parts in cooperative relationship as hereinafter more particularly pointed out in the claims.

In the drawings:

Figure 1 is a side elevation of a nylon pre-boarding apparatus within my invention;

Fig. 2 is a plan view of the apparatus shown in Fig. 1;

Fig. 3 is an elevation taken from the left of Figs. 1 and 2;

Fig. 4 is a sectional detail view substantially on the line 4—4 of Fig. 3, looking in the direction of the arrows;

Fig. 5 is a sectional plan view substantially on the line 5—5 of Fig. 1;

Fig. 6 is a sectional elevation substantially on the line 6—6 of Fig. 2;

Fig. 7 is a cross-section substantially on the line 1—7 of Fig. 1, looking in the direction of the arrows;

Fig. 8 is a sectional detail view substantially on the line 8—8 of Fig. 2, looking in the direction of the arrows;

Fig. 9 is a diagrammatic view of the circuits for the motive fluid used in operating the apparatus shown in Figs. 1 through 8; and

Fig. 10 is a diagram of the electrical circuits used to operate certain of the valves shown in Fig. 9.

The invention is shown in the accompanying drawings as applied to an illustrative embodiment of the invention in the form of an apparatus for heat treating articles in a live steam atmosphere. Said apparatus is expected to find large use for pre-boarding nylon hosiery, but is not limited to such use. As is well known, silk hosiery is stretched over thin boards or forms while wet and heated while on said forms to give them the desired finish and flat form preparatory to packing. In the case of nylon hosiery, it has been found necessary to heat the articles

on the forms prior to the dyeing and boarding operations to a temperature higher than that ordinarily used with silk hose, in order to permanently set the yarn formation of nylon stockings in the proper shape. As saturated steam is the heating medium recommended for the pre-boarding step, apparatus according to my invention is well adapted to this purpose, although this use is merely illustrative.

An apparatus in accordance with my invention comprises a chamber having a motor operated door and a motor operated lock for said door. Preferably, but not necessarily the motor or motors for the door and for the lock are operated by pressure fluid, which may be compressed air, and said fluid is preferably, but not necessarily, controlled by electrically operated valves. In order to economize time and space, it is preferred that said door be of the hingeless type and the locking means therefor arranged to act on at least two opposite sides of the door.

Referring to the drawings more in detail, a treating chamber 12, shown in Figs. 1 to 7 inclusive, is provided with a pair of track members 5 and a cross member 6 secured thereto, the track members 5 providing means on which a truck or other carrier device (not shown), for the heretofore mentioned stocking forms, may be moved into the chamber to the extent controlled by the cross or stop member 6. Said chamber also has a substantially rectangular door 14 (Fig. 3) at one end, without hinges and arranged to slide up and down in channels 15 (Fig. 5) in guide members 16 on opposite sides of the door. Motion of door 14 is produced by two vertical reciprocating piston-type double acting motor cylinders 18, one on each side of the door. The piston rod of each cylinder 18 is extended upward in form of a rack 19 having teeth 20 (Fig. 8) on the edge toward the door 14. Racks 19 are spaced from the vertical edges of the door as shown in Figs. 4 and 8, to provide space for a pair of gears 21 and 22 between each rack 19 and the door 14, gears 21 and 22 being mounted to rotate in boxes 23 which are fixed to the upper ends of guides 16 and which serve also to support the outer edges of racks 19. As plainly shown in Figs. 3 and 8, the vertical edges of door 14 are provided with rack teeth 24 which mesh with the teeth of gears 22, while gears 22 mesh with gears 21 and they, in turn, mesh with rack teeth 20. It follows that the door 14 has the same motion as and goes up and down at the same times as the racks 19. The cylinders 18, therefore are placed near the floor level and, in order to open the door, motive fluid is introduced into the lower ends of the cylinders 18 beneath the pistons, the upper ends of cylinders 18, at the same time exhausting the motive fluid previously introduced into the upper ends of the cylinders. In order to close door 14, when so desired, motive fluid is introduced into the upper ends of cylinders 18 above the pistons as the lower ends exhaust the motive fluid therefrom.

As best shown in Figs. 1, 2, 4 and 6, to ensure that racks 19 shall remain in exact synchronism and to maintain the vertical edges of door 14 exactly parallel to the guides 16 to prevent jamming of the door in the guides, the gears 22 are simultaneously operated by a horizontal shaft 29 connected at each of its ends by bevel gearing 30 to gudgeons 31 journalled in boxes 23 on which gears 22 are mounted. As is clear from the drawings, shaft 29 is mounted to the rear of door 14, but gudgeons 31 project forward to the

front of the door and have squared ends 32 whereby a crank may be applied to a gudgeon to move the door by hand when desired.

The processing medium used in chamber 12 is preferably live steam so that the door structure must be designed to contain pressure within chamber 12. For this purpose, the open end of the chamber 12 is provided with a recess 25 which extends entirely around the doorway or opening and has seated therein a packing 26 which projects from the vertical end face of the chamber and is adapted to make a steam tight joint with the smooth inner face of the door 14 when the door is forced against the packing. The outer face of door 14 has insulation 28 thereon but the insulation extends short of the edges of the door on its vertical edges so that space is provided therealong for means to press the door against said packing. As above mentioned, the door shown is of the hingeless type. This is partly for the reason that I have found it to be difficult to obtain a uniform pressure on all sides between the door and the chamber or packing when the door is of the hinged type. Further, I have found that the non-swinging type of door requires less floor space and can be opened and closed more quickly.

In order to apply pressure to the door to close it tight against internal pressure, I have provided two locking mechanisms, one for each vertical edge of door 14. Said mechanisms each comprises a clamp or locking lever 34 of shallow U-form in plan as shown in Fig. 5 and forked in elevation as shown in Fig. 3. Each locking lever 34 is pivotally mounted on a shaft 35 carried by one of the members 16 and arranged so that its inner end can bear against the front face of door 14 near one of its vertical edges and about midway thereof. Springs 41 mounted between each locking lever and its associated member 16, tend to bias the lever from locking engagement with the door 14. The outer end of each locking lever 34 is engageable with one end of a rod 36 mounted to slide in a guide block 37 fixed to the side of the chamber 12. At its other end each rod 36 is pivotally connected to a link 38 which is pivotally connected in turn to a bell-lever 39, best shown in Fig. 1, which is pivoted at 40 to the side of the chamber 12 so as to swing in a vertical plane. The arm of each bell-lever 39 which connects with a link 38 is substantially horizontal as shown in Fig. 1 when the locking levers 34 are pressed against the face of door 14 to seal the open end of the chamber 12; the rod 36, link 38 and arms of levers 39 forming at this time toggles acting to apply great pressure on the door in proportion to the force actuating levers 39. A stop pin 42 is set on each side of chamber 12 in position to stop a lever 39 from overtraveling the position of substantially greatest pressure on door 14.

The other arms 44 of bell-levers 39 are connected by a cross-bar or equalizing lever 43 which extends horizontally beneath chamber 12 and connects the depending arms 44 as best shown in Fig. 7. The ends of lever 43 are pivoted to lever arms 44 and, at its center, lever 43 is pivotally connected to the piston rod 45 of a double acting motor cylinder 46 which is arranged horizontally beneath chamber 12 with the axis of the cylinder parallel to that of the chamber. When motive fluid is admitted into the rear or right hand end of cylinder 46 as viewed in Fig. 1, piston rod 45 is forced forward toward the door thereby forcing the locking

levers 34 against the front face of the door by the above described mechanism to seal the open end of the chamber 12. When motive fluid is admitted to the front end of cylinder 46, the end nearer the door, the levers 34 are thrown to the unlocking position by the action of springs 41, as the arms 44 are drawn away from the door 14 and the other arms of levers 39 are thereby drawn from the horizontal position shown in Fig. 1.

Steam for heating chamber 12 is introduced under pressure through pipe 47 which is shown in Figs. 1 and 9 as having a hand operated cut-off valve 48 therein as well as a motor operated inlet valve 49. Pipe 47 enters chamber 12 at a point 51 somewhat above the bottom of the chamber so as to direct the steam against a baffle plate 17 and prevent it from directly striking the articles being treated. The outlet pipe 52 for exhausting steam from chamber 12 through a motor operated outlet or exhaust valve 54, connects with the chamber at a point 53 which is as low in the chamber as possible so that any condensation may readily drain therefrom. Condensate from the steam line 47 is passed to drain pipe 11 through intermediate connections comprising a filter 4, a pipe 3, a water trap 9 and a pipe 7. Likewise, the condensate from the chamber 12 is passed to drain pipe 11 through intermediate connections comprising outlet pipe 52, water trap 10 and the pipe 7. Valves 49 and 54 are operated in one direction by springs, one of which is shown at 55 in Fig. 1, and in the other direction by diaphragms contained in casings 56, motive fluid being introduced on top of the diaphragm in each case to operate the valve in said other direction. However, the arrangement is different in the two cases; in the case of the inlet valve 49, the spring 55 holds the valve normally closed and the pressure of the motive fluid on the diaphragm must overcome the action of the spring in order to open the valve; whereas in the case of exhaust 54, the spring holds the valve normally open and the pressure of the motive fluid on the diaphragm must overcome the action of the spring in order to close the valve. In this way, there is a minimum chance of accidents occurring through the admitting of steam into chamber 12 unintentionally, or of retaining steam pressure in chamber 12 longer than intended. As appears in Fig. 9, the steam supply line or pipe 47 may contain a pressure regulator or reducing valve 57 in case the pressure of the boiler for supplying steam to line 47 is greater than that for which chamber 12 is designed, and may also contain a filter 8 and a pressure gauge 50 to indicate the pressure of the steam passing through supply line 47.

The preferred motive fluid for operating the pistons of motors 18 and 46 and the diaphragms of valves 49 and 54 is compressed air and, in Fig. 9, I have shown somewhat diagrammatically the pipes for supplying air to the opposite ends of motor cylinders 18 and 46 and to the diaphragm casings 56; a pipe 59 being shown for connection to a supply of compressed air which serves as motive fluid. Pipe 59 is shown as containing a hand cut-off valve 60 and a reducing valve or pressure regulator 61, a pressure gauge 33 to indicate the pressure of the air as controlled by pressure regulator 61 and oiler 13 for lubricating the solenoid operated valves hereinafter described.

For controlling the flow of motive fluid to said

10 diaphragm casings 56 and to said cylinders 18 and 46, I have provided, as best shown diagrammatically in Fig. 9, a group E of twelve similar and normally closed electro-magnetic or solenoid operated valves located in a control box 58, Figs. 1 and 2. The valves of group E are all biased by springs or gravity to the closed position and are opened only when current flows in their solenoid windings, and they are arranged at three different levels. The valves at each level are connected two on each side of a central vertical extension 62 of air pipe 59.

15 Shown at the top level (Fig. 9) are two air inlet valves 63 and 64 and two air outlet valves 65 and 66. Valves 63, 64, 65 and 66 are all set in a horizontal cross-pipe 67, which connects to pipe 62 so as to run in both directions therefrom and the outer ends of which are connected to exhaust pipes 69. Intermediate valves 63 and 65 20 on one side of central pipe 62, a pipe 70 leads off from pipe 67 to the casing 56 of the valve 49 for admitting steam to chamber 12. Intermediate valves 64 and 66 on the other side of pipe 62, a pipe 71 leads off from pipe 67 to the diaphragm casing 56 of valve 54. The operating coils of valves 63 and 64 are connected to be energized at the same time, so that valves 63 and 64 will open at the same time, valves 65 and 66, however, then remaining closed. Motive fluid in the form of pressure air will therefore enter pipes 70 and 71 simultaneously to alter the position of valves 49 and 54 as previously set by their springs 55, pressure in pipes 70 and 71 opening valve 49 and closing valve 54 so that, the door 14 being closed and locked, steam pressure from steam pipe 47 will build up in chamber 12 and will remain in operation as long as desired. When valves 63 and 64 are allowed to close, valves 65 and 66 may 25 be opened to exhaust the air pressure from diaphragm casings 56, whereupon springs 55, will reverse the positions of valves 49 and 54 to cut off chamber 12 from the steam supply and to open chamber 12 to the exhaust. In the pipe 62, between the valves of the top and second level, is a 30 valve 68 for regulating the pressure of the air exerted against the diaphragms of valves 49 and 54, the air pressure being indicated by a gauge 27, also in the line 62.

35 The four electro-magnetic valves on the second level in group E control the flow of motive fluid to and from the two ends of motor cylinders 18 and are set in a cross-pipe 72, valves 73 and 74 which lie next the pipe 62 on opposite sides thereof serving to admit motive fluid to the lower and upper ends respectively of the cylinders 18 and valves 75 and 76, which lie next to exhaust pipes 69, serving to discharge motive fluid from the lower and upper ends of cylinders 18. For 40 conducting motive fluid to and from the lower ends of said cylinders, pipe 77 opens off of cross-pipe 72 between valves 73 and 75 and is branched at the end nearer cylinders 18 so as to connect with both cylinders. Similarly, a pipe 78 opens off of cross-pipe 72 between valves 74 and 76 and is branched at the end nearer the cylinder 18 so as to connect with the upper end of both said cylinders to conduct motive fluid thereto and therefrom. However, as the pistons in cylinders 18 45 operate because of the pressure differences on their two sides, it is necessary to operate the valves 73 and 76 simultaneously and the valves 74 and 75 simultaneously, so that the motive fluid on the one side of the pistons in the cylinders may 50 exhaust at the same time the motive fluid enters

on the other sides of the pistons. When valves 73 and 76 have been opened by current flowing in their actuating coils, motive fluid flows from pipe 62 through pipe 72, valve 73 and pipe 71 into the lower ends of the cylinders 18 and the motive fluid exhausts from the upper ends of the cylinders through pipe 78, valve 78 and left hand exhaust pipe 69, so that the pistons rise and open door 14. When valves 73 and 76 have been permitted to close by cutting off the current in their circuits and valves 74 and 75 have been opened by current flowing in their actuating coils, the reverse flow of motive fluid occurs and the pistons fall and close the door.

At the lowest level of group E are four electromagnetic valves 79, 80, 81 and 82 which control the flow of motive fluid to and from the ends of cylinder 46. Valves 79, 80, 81 and 82 are set in a cross-pipe 83 which runs from central pipe 62 both ways to exhaust pipes 69. Valves 79 and 80 lie next the central vertical pipe 62 on opposite sides thereof and valves 81 and 82 lie next the pipes 69, valve 81 lying on the same side of the pipe 62 as valve 79. Between valves 79 and 81, a pipe 84 leads off of pipe 83 to conduct motive fluid to and from one end of cylinder 46. Between valves 80 and 82, a pipe 85 leads off of pipe 83 to conduct motive fluid to and from the other end of cylinder 46. Since motive fluid must exhaust from one side of the piston in cylinder 46 at the same time that it is admitted at the other side of the piston, valves 79 and 82 are opened and closed simultaneously and valves 80 and 81 are opened and closed simultaneously. When current is supplied to the operating coils of valves 79 and 82, these valves are opened against their biasing springs and motive fluid flows into cylinder 46 through pipe 84 and out of pipe 85 to move the piston in cylinder 46 in the direction to bring toggle link 38 in line with the pivot 40 and to lock door 14. When current is supplied to the operating coils of valves 80 and 81 to open them against their biasing springs, motive fluid flows into cylinder 46 through pipe 85 and out through pipe 84 to move the piston in cylinder 46 in the direction to throw link 38 out of line with pivot 40 and to unlock door 14.

Electrical interlocks

In order to assure the desired sequence of operations and thereby prevent accidents, I have provided safety means in the form of interlocks between the door operating means and the lock operating means, between the lock operating means and the diaphragm operated steam inlet valve and between the internal pressure in chamber 12 and the lock operating means. The interlocking arrangements shown are of electrical character, but I do not limit myself to this.

The interlock between the door operating means and lock operating means comprises an angle 86 fixed to a side of one of racks 19 in such position that when door 14 is fully closed as shown in Fig. 3, angle 86 contacts a member 88 shown in the form of a roller pivotally mounted at the end of a lever 89 engaged with a spindle 90 so as to turn the spindle. Spindle 90 operates a switch 91 in the circuits of the coils for opening valves 79, 80, 81 and 82 controlling the motor cylinder 46 which operates the locking means. Roller member 88, lever 89 and switch spindle 90 are so arranged that when the door 14 is not fully closed, a spring keeps the spindle 90 in position to ensure that the circuits for operating valves 79, 80, 81 and 82 remain

open and the valves themselves therefore remain closed. When, however, angle 86 holds roller 88 as far down as possible, the switch in box 91 will permit the circuits of valves 79, 80, 81 and 82 to pass current whenever closed and otherwise permitted by the other means herein disclosed for controlling the various circuits.

As best shown in Fig. 1, the interlock between the lock operating means and the valve 49 for controlling the admission of steam to chamber 12 comprises a lug 92 on the side of lever 39 through which extends a link 93 which is pivotally connected at one end to a lever 94 which has driving engagement at the end opposite link 93 with a spindle 95 which extends into a switch 96 controlling the circuits for operating the valves 63 and 65 which control the opening and closing of valve 49 in the line for supplying steam to chamber 12. Link 93 has a collar 98 fixed thereon and a compression spring 99 is carried on the link and pressed at its two ends against lug 92 and collar 98. Consequently, unless the lever 39 is in the position shown in Fig. 1 in which the locking means for door 14 is in fully locked position, lug 92 presses link 93 through spring 99 so as to keep the switch in box 96 open. Valves 63 and 65 are thereby prevented from opening until the lever 39 in the locking means is in the fully locked position and the same is true also of valve 49, so that live steam cannot be admitted to chamber 12 unless the door 14 is fully closed and locked.

Similarly, it is necessary to prevent the door 14 from being unlocked unless the steam pressure in the chamber has been lowered to substantially atmospheric pressure. For this purpose an interlock is provided comprising a pressure operated switch 100 which is placed in the circuit for operating valves 73 and 76 controlling the unlocking action of the motor cylinder 46. Said pressure operated switch connects by means of pipe 101 with the interior of chamber 12. Switch 100, which is provided with a piston or diaphragm, is arranged to maintain the circuits of valves 80 and 81 open so that the door 14 cannot be unlocked after a steam exhaust valve 54 has opened until the steam pressure in chamber 12 has dropped practically to zero.

Electrical circuits

The arrangement herein disclosed includes means whereby it is necessary only for the attendant to push a button in order, when the door is open, to close the door 14, to lock it, to close the exhaust and to turn on the steam. After the steam pressure has been on for a period determined by a timing means, the reverse process is initiated by said timing means and thereupon carried out automatically. The circuits for controlling said valves 63 through 66, 73 through 76, and 79 through 82, respectively, are shown diagrammatically in Fig. 10. In Fig. 10, the conducting elements which appear in the diagram are shown in black, and structural elements are shown only in outline. In Fig. 10, the solenoid windings of valves 63 through 66, 73 through 76, and 79 through 82, respectively, are shown diagrammatically and are given reference characters consisting of the reference character of the corresponding valve with the suffix "w." Thus, the reference character for the winding for valve 63 is 63w and that for the winding of valve 82 is 82w. Along one side of the diagram of Fig. 10 extends a supply circuit 102 between the opposing sides of which a difference of potential is

maintained. The two sides of circuit 102 are connected to buses 103 and 104, respectively, through disconnect switch 105. A cycle of operations of chamber 12 is started by the operator by closing a circuit, which is effected by pushing on a button-type control switch 106.

Inasmuch as the button 106 is normally biased to its open position indicated in Fig. 10, by means not shown I provide means whereby the remainder of the cycle is carried out automatically after button 106 has once been closed regardless if the operator removes his hand from button 106 after a moment or so and allows the button to open its circuit. The various means employed for this purpose will be indicated in connection with circuits in which they are employed, but they include, in addition to certain circuit connections and the parts previously mentioned, a master switch 111 of the electro-magnetic type, two switches 124 and 125 of electro-magnetic type each having four fixed and four movable contact points, a switch 91 operated by the door, a switch 96 operated by the locking means, an indicating lamp 128, a timing motor M, a pressure operated two-point mercury switch 130 in the circuit of said timing motor and a pressure operated four-point mercury switch 100 in the circuits of the electrically operated valves 78 through 82 controlling the locking and unlocking operations.

The circuit in which button 106 is included starts at point 107 on bus 103 and runs through lead 108 to a solenoid winding 109 of a multiple contact solenoid switch 111 to lead 112, through lead 112 to plate 113 in connection board F, from connection board F through lead 114 to said button 106 and from button 106 through lead 115 to plate 116 of board F, and from plate 116 through lead 117 to a point 110 on bus 104. Upon the closing of said circuit through button 106, winding 109 being energized, a movable contact 119 in switch 111 is swung over from a position in which it is in engagement with contact 120, to a position shown in Fig. 10 in which it is in engagement with a contact 121. At the same time that contacts 119 and 121 are brought into conductive engagement, contacts 122 and 123 in switch assembly 111 are also pressed together to make conductive engagement, whereas they were previously separated enough to prevent passage of current.

Switch 111 having moved contact 119 to the right into engagement with contact 121 and pressed contacts 122 and 123 into close engagement, it remains in this position until its original contact grouping is restored by the timing motor M by breaking the current carrying engagement between contacts 122 and 123 and by swinging contact 119 to the left out of engagement with contact 121 and into current carrying engagement with contact 120. As the operator can only close switch 106 and as the opening of switch 106 has no effect on the master switch 111, the arrangement prevents the operator from shortening the operating cycle when it has once started by inadvertently pushing the button.

The first operation initiated when the switch 111 has been actuated by closing the button circuit is the closing of the door 14. At this time, switches 124 and 125 are both in their unexcited condition in which their lower movable contacts a and b rest by gravity against their lower fixed contacts c and d, but upon a current carrying engagement being established between contacts 119 and 121, a circuit is established running from

point 132 on bus 103 through lead 133 and operating coil 134 to lead 135, through lead 135 to contact 121 and contact 119, and from contact 119 through leads 136 and 137 to bus 104 at a point 138. The coil 134 being thus energized, its left upper movable contacts e and right upper movable contact f are drawn up against their upper fixed contacts g and h, respectively, and a circuit for operating valves 74 and 75 to open them and to close door 14 is thereby established as follows: from point 139 on bus 103 through lead 141 to plate 142 on board G, from plate 142 through lead 143 and point 144, from point 144 in both directions along lead 145 to and through coils 74w and 75w to lead 146, along lead 146 in opposite directions to point 147, along lead 148 to plate 149 on board G, from plate 149 along lead 151 to and through lead 152 to movable contact f in switch 124, from movable contact f to fixed contact h, from contact h to lead 153 to point 154, from point 154 along lead 155 to point 156 on bus 104.

In order to assist the operator in keeping track of whether the automatic switches 111, 124 and 125 are operating correctly, the pilot lamp 128 is arranged so as to light as soon as switch 124 has been raised to its upper position by the energization of its coil 134. The circuit for this purpose begins at point 118 on bus 103 and extends through lead 262 to bar 263 in board F, from bar 263 through lead 264 to lamp 128, from lamp 128 through lead 265 to bar 266 on board F, from bar 266 through lead 267 to point 268, from point 268 along lead 151 to point 269 on lead 152. The coil 134 of switch 124 having been energized by the completion of its circuit by the movable contact 119 of switch 111 in engaging contact 121 and the movable contacts of switch 124 therefore being in their upper positions, the circuit of lamp 128 then is extended from lead 152 to movable contact f of switch 124, from contact f to upper fixed contact h of switch 124, from said contact h to lead 153 and point 154 thereon, and from point 154 through lead 155 to bus 104 at point 156. The lighting of lamp 128 therefore indicates correct operation of switches 111 and 124. As explained more fully hereinbelow, the operation of switch 125 provides a second circuit for lighting lamp 128, so that it does not go out at the time switch 124 loses its holding current in coil 134.

Valves 74 and 75 now being open, motive fluid flows into the upper ends of cylinders 18 to close door 14 and the next operation performed is to lock the door. This is performed automatically as follows: when the door is fully closed, angle 86 throws switch 91 into the up position as shown in Fig. 10 in order to establish a circuit from point 139 on bus 103 through lead 141, plate 142 and lead 143 to point 157, from point 157 along lead 158 in opposite directions to and through coils 79w and 82w, from coils 79w and 82w along lead 159 in opposite directions to point 161, from point 161 along lead 162 to plate 163 in board G, from plate 163 through lead 164 to branch point 165, from point 165 through lead 166 to left upper movable contact e in switch 124, from contact e to fixed contact g, from contact g through lead 167 to plate 168 in board F, from plate 168 through lead 169 to contact 171 of switch 91 to and through connector bar 172 of the switch to contact 173, from contact 173 to lead 174, from lead 174 to and through leads 175 and 176 to lead 115 and thence through plate 116 and lead 117 to point 110 on bus 104. Coils 79w and 82w having been thus energized,

valves 79 and 82 are opened as shown in Fig. 10 and motive fluid is caused to flow in cylinder 46 so as to lock the door 14. The locking means having operated, switch 96 is thereby thrown over into the position shown in Fig. 10 and the switch 125 is thereupon operated as a preliminary to the performance of the next step in the automatic cycle, namely that of supplying heat to chamber 12. Said switch 125 includes a solenoid coil 177 and, upon movement of switch 96 into the position shown in Fig. 10, a circuit is established through coil 177 as follows: from bus 103 through lead 178 through coil 177 and thence through lead 179 to plate 181 on board F, from plate 181 to lead 182 to upper right hand contact 183 of switch 96, through movable connecting bar 184 to fixed contact 185, from contact 185 to lead 186, through lead 186 to point 187 on lead 176 and thence through lead 115, plate 116 and lead 117 to bus 104. Coil 177 having been energized, the upper movable contacts *e* and *f* of switch 125 are drawn up against its upper fixed contacts *g* and *h* and the circuits for operating the steam valves are then established as follows: from point 139 on bus 103 through lead 141, plate 142 and lead 143 to branch point 188, from point 188 in opposite directions along lead 189 to and through coils 63w and 64w and along lead 191 in opposite directions to point 192, from point 192 to lead 193, from lead 193 to plate 194, from plate 194 through lead 195 to movable contact *f* of switch 125 and therethrough to fixed contact *h*, from contact *h* into lead 135 and therethrough to contact 119 and thence to bus 104 by a route previously traced. Coils 63w and 64w having been energized valves 63 and 64 are opened to permit motive fluid to open the steam inlet valve 49 and close steam outlet valve 54 so that steam pressure can build up in chamber 12.

When coil 177 has been energized and the movable contacts of switch 125 have therefore been raised to the position shown in Fig. 10, a parallel circuit is thereby provided for current through lamp 128 as follows: from point 118 on bus 103 through lamp 128, to point 269 as previously traced, from point 269 at the junction of leads 151 and 152 to the right along the lead 152 to movable contact *e* of switch 125, from contact *e* to upper fixed contact *g* of switch 125, from said contact *g* to the left along lead 153 to point 154 and from point 154 through lead 155 to bus 104 at point 156. Therefore, the continued burning of lamp 128 after the time that the timing means M has operated to break the circuit through the coil 134 of switch 124 is an indication that the switch 125 is operating properly.

Steam pressure in chamber 12 having reached a certain point, mercury switch 130 is thrown into the position shown in Fig. 10 and thereupon a circuit is closed through the timing motor M as follows: from point 107 on bus 103 through lead 108 to branch point 196, from point 196 through lead 197 to and through motor M to lead 198, through lead 198 to plate 199 of board F and thence through switch 130 to lead 201, through lead 201 to plate 202 to lead 203, through lead 203 to contact 122 and thence to contact 123, and from contact 123 through lead 137 to bus 104 at point 138.

At the same time that mercury switch 130 is turned to the position shown in Fig. 10, the four-contact of two-circuit mercury switch 100 is turned by means (not shown) operated by the steam pressure to the position shown in Fig. 10. Thereby the mercury closes the gap across the 70

left hand pair of contacts in switch 100 and a holding circuit is established whereby coils 79w and 82w of the valves 79 and 82 are maintained in energized condition and the locking means maintained under positive pressure of the operating fluid to prevent any accidental unlocking of the door. This condition is maintained until the pressure in chamber 12 has gone down to a point at which it is safe to unlock the door, preferably approximately atmospheric pressure. The said safety holding circuit runs as follows: from point 139 on bus 103, along lead 141 to plate 142 of board G, from plate 142 along lead 143 to point 157, from point 157 along lead 158 and through coils 79w and 82w to lead 159 and point 161, from point 161 along lead 162 to plate 163, from plate 163 along lead 164 to point 165, from point 165 along lead 160 to plate 170 of board F, from plate 170 along lead 150 to switch 100 and thence through lead 223 and point 224, and from point 224 through lead 115, plate 116 and lead 117 to bus 104.

10 The timing motor M having been energized it continues to run for a predetermined length of time, after which motor M throws contact 119 to the left into current carrying engagement with contact 120 and breaks the current carrying engagement between contacts 119 and 121 and between contacts 122 and 123. Timing motor M 15 therefore remains inoperative for the rest of the cycle because its circuit is broken between contacts 122 and 123.

20 The cycle of operations thereupon proceeds automatically as follows: The contact 119 having moved to the left from the position shown in Fig. 10, the circuits through coils 63w and 64w are broken at the point between contacts 119 and 121 and valves 63 and 64 therefore close. Steam inlet valve 49 is thereby permitted to close and steam outlet valve 54 to open as soon as the motive fluid is permitted to discharge from above the operating diaphragms in chambers 56 of valves 49 and 54. Also the holding circuit through coil 134 of switch 124 is broken at contact 121 and the lower movable contacts *a* and *b* of switch 124 thereupon drop down on fixed contacts *c* and *d* respectively, while the upper movable contacts *e* and *f* of switch 124 lose current carrying engagement with fixed contacts *g* and *h* respectively.

25 At the time that swinging contact 119 engages contact 120 circuits are thereupon established for closing the steam inlet valve 49 and opening the steam outlet valve 54, as follows: from bus 103 at point 139 through lead 141, plate 142 lead 143 to point 188 and lead 189 as traced heretofore, from lead 189 through coils 65w and 66w to lead 204, along lead 204 in opposite directions to point 205, from point 205 along lead 206 to plate 207 of board G, from plate 207 through lead 208 to point 209, from point 209 along lead 211 to contact 120 and thence through contact 119 and leads 136 and 137 to bus 104 at point 138. Coils 65w and 66w having thereby been energized, valves 65 and 66 are opened to permit the motive fluid, which had operated valves 49 and 54, to escape and valve 49 is therefore closed by its spring at the same time that valve 54 is opened by its spring. Further, the movable contacts of switch 124 having dropped from the position shown in Fig. 10, the circuit for opening valves 79 and 82 is broken at contacts *g* and *e* of switch 124 so that valves 79 and 82 may close as soon as the pressure in chamber 12 has dropped to such a point that the holding circuit through

the right hand contacts of switch 100 is broken due to the switch reversing its inclination. As valves 79 and 82 direct the motive fluid into cylinder 46 in the direction to lock door 14, the closing of these switches clears the way for the opening of the door 14 at the proper time.

Steam inlet valve 49 having been closed and steam outlet valve 54 having been opened, the steam pressure in chamber 12 begins to fall and, when it has fallen a predetermined amount, preferably substantially to atmospheric pressure, the mercury switch 100 assumes the inclination opposite to that shown in Fig. 10, so that circuits previously traced for holding the lock in locking position are broken at switch 100 and circuits for opening valves 80 and 81 to unlock door 14 are established as follows: from point 139 on bus 103 to and through lead 141 to point 157 on lead 158 as previously traced, along lead 158 in opposite directions from point 157 to and through coils 80w and 81w to lead 212, along lead 212 in opposite directions toward point 213, from 213 through lead 214 to plate 215 of board G, from plate 215 through lead 216 to point 217, from point 217 through lead 218 to fixed contact c of switch 124, from contact c to contact a of switch 124 and thence through lead 219 to plate 221 of board F, from plate 221 of board F through lead 222 to the right pair of contacts in mercury switch 100 and through them and the mercury to lead 223, along lead 223 to point 224, and from point 224 along a course previously traced through lead 115, plate 116 and lead 117 to bus 104.

Operation of unlocking piston 46 moves switch 96 to the left from the position shown in Fig. 10, thereby breaking, at switch 96 the circuit through operating coil 177 of switch 125 and permitting the movable contacts *a* and *b* of switch 125 to drop down and make contact with the lower fixed contacts *c* and *d* of this switch while movable contacts *e* and *f* of switch 125 break contact with their opposed upper fixed contacts *g* and *h*. Contact having been broken at points *e* and *g* of switch 125, the circuit through coils 74w and 75w is broken and the valves 74 and 75 therefore close so that the pistons in cylinders 18 may be moved to open the door 14 as soon as valves 73 and 76 are opened. Circuits for opening valves 73 and 76 are then established as follows: from point 139 on bus 103 through lead 141, plate 142 and lead 143 to point 144, from point 144 along lead 145 to and through coils 73w and 76w to lead 245 and along it to point 246, from point 246 along lead 247 to plate 248 of board G, from plate 248 along lead 249 to contact *a* in switch 125, from contact *a* to contact *c* in switch 125, from switch 125 along lead 251 to contact *d* of switch 124, from thence to contact *b* of switch 124 and thence through lead 252 to point 253 and thence through lead 155 previously traced to bus 104 at point 156.

The door 14 having opened, the switch 91 is permitted to move from the position shown in Fig. 10 to one in which a lower connecting bar 254 will rest on contacts 255 and 256. Circuits will thereupon be established thereby as follows: from point 139 on bus 103 through lead 141, plate 142 of board G and lead 143 to point 157. From point 157 in both directions along lead 158 to and through coils 80w and 81w to lead 212, along lead 212 in both directions to point 213, from point 213 along a course previously traced through lead 214, plate 215 of board G and lead 216 to point 217, from point 217 along lead 257 to plate 258

of board F, from plate 258 along lead 259 to said contact 256, from contact 256 through connecting bar 254 to contact 255, from contact 255 along lead 260 to point 261, and from point 261 along a course previously traced through lead 222 the right pair of contacts of mercury switch 100 to lead 223, point 224, lead 115, plate 116 and lead 117 to bus 104. The coils 80w and 81w being thus energized by a holding circuit, the valves 80 and 81 are held open and the motive fluid is supplied to cylinder 46 in such a direction as to hold the locking means positively in the off position until the operator initiates another cycle by pushing button 108.

Operations

After the operator places the articles to be treated within the chamber 12 and presses the starting switch 106, the following cycle of operations is performed: The circuit is closed to the master switch 111, whereupon the solenoid switch 124 is energized thereby, closing the circuit to the solenoid-operated air valves 74 and 75, which valves are accordingly opened, and opening the circuit to the solenoid-operated air valves 73 and 76, which valves are accordingly closed, the valve 74 supplying air to the top of the door cylinders 18 to close the door 14, and the valve 75 functioning to exhaust the air from the bottoms of the cylinders 18. Upon energizing the switch 124 the circuit is closed thereby lighting the pilot light 128 which indicates to the operator that the chamber is in a fabric treating cycle.

As the door reaches its closed position the switch 91 is operated to close the circuit to the solenoid-operated valves 79 and 82, the valve 79 is accordingly opened to supply air to the right end of the door lock cylinder 46, whereas the valve 82 is opened to exhaust the air from the left end of the cylinder 46, thereby causing levers 39 and associated parts to operate the lock levers 34 so as to seal the open end of the chamber 12.

The latter part of the movement of levers 39 to lock the chamber 12 operates the switch 96, closing the circuit to and energizing the solenoid switch 125 which in turn closes the circuit to and energizes the solenoid operated air valves 63 and 64, the valve 64 closing the steam exhaust valve 54, and the valve 63 opening the steam inlet valve 49, whereupon steam is admitted into the chamber 12. As the steam enters the chamber 12, the air in the chamber is exhausted through valves 87 which communicate with the interior of the chamber by means of pipes 97.

When the steam pressure within the chamber 12 reaches a predetermined value, the switch 130 is operated to close the circuit to the timing device M, which timing device operates to control the length of time that the articles are exposed to the action of the processing treatment. At the same time that the switch 130 is operated, the switch 100 is operated by the steam pressure in the chamber 12 and functions to keep the solenoids of the valves 79 and 82 energized, this action keeping the valves 79 and 82 open and the levers 34 in clamping engagement with the door 14. A thermometer 126 and gauge 127 communicating with the interior of the chamber 12 are provided to indicate the temperature and the pressure of the steam within the chamber during the processing cycle. A pressure relief valve 129 is also provided to prevent the steam pressure in the chamber from becoming excessive.

After the steam pressure has been maintained at a predetermined value within the chamber 12 for the required length of time, as determined by the timing mechanism M, the switch 111 is automatically operated to open the circuit, whereupon the solenoid of switch 124 is deenergized and the circuit through switch 125 to the valves 74 and 75 is consequently broken, thereby causing these valves to close and opening the circuit to the pilot light 128. Simultaneously with the operation of switch 111 to open the one circuit and thereby deenergize the switch 124, the switch 111 also functions to close a second circuit and energize and open valves 65 and 66 to exhaust the air from the diaphragm casings 56 of valves 49 and 54 thereby closing the steam inlet valve 49 and opening the exhaust valve 54, whereupon the steam is exhausted from the chamber 12. As the steam pressure in the chamber is reduced to substantially atmospheric pressure, the switch 100 is rotated to close the circuit across the right hand contacts, Fig. 10, which action breaks the circuit to deenergize and close the valves 79 and 82 and to energize and open valves 80 and 81; the valve 80 thereupon permitting air pressure to be applied to the left end of cylinder 46, and the valve 81 exhausting the air from the right side of the cylinder 46, thereby operating the cylinder 46 and lever 39 to release the levers 34 for clamping engagement with the door 14.

Operation of the lever 39 to release the locking levers 34 also operates switch 96 to open the circuit and deenergize the solenoid of switch 125, opens the circuit to the valves 74 and 75 and thereby closes these valves, and also closes the circuit from the switch 125 through switch 124 to open the valves 73 and 76; the valve 76 opening the exhaust line to the tops of cylinders 18, and the valve 73 opening the air line to the bottoms of the cylinders to open the door 14. As the door 14 opens, the switch 91 automatically operates to close the circuit to the valves 80 and 81 thereby keeping these valves open, to thereby prevent operation of the cylinder 46 while the door 14 is open. Likewise, the circuit to the valve 73 remains closed so as to hold the door in raised position, and the circuit to valves 65 and 66 also remains closed to hold the steam inlet valve 49 closed and the exhaust valve 54 open and thereby prevent steam from being accidentally admitted to the chamber 12 while the door 14 thereof is open. At this stage, the processing having been completed, the operator removes the treated articles from the chamber.

After reloading the chamber with another set, the operator again operates the starting switch 106 whereupon the apparatus operates to repeat the processing cycle above set forth.

Although this device has been found particularly effective in so far as polyamide articles are concerned, nevertheless, it is to be understood that beneficial results may also be obtained by using this apparatus in connection with the treating of articles composed of other yarns, such for instance as of silk, whose properties are dissimilar to those of polyamide yarns.

Although various terms, such as "pressure air, pressure fluid, motive fluid, compressed air" etc., have been used herein when referring to the medium employed in the door operating and door locking motors, it is to be understood these terms are used to designate any medium which when utilized as herein set forth will function to effect the results explained. Similarly, although "pres-

sure heating medium, fluid heating medium, heating medium, heating means, processing medium, steam" etc., have been used to designate the medium supplied to the article treating chamber 5 for processing the articles therein, it is to be understood that whichever term is used, it is to be construed in its broadest sense.

Of course, the improvements specifically shown and described by which I obtain the above results, can be changed and modified in various ways without departing from the invention herein disclosed and hereinafter claimed.

I claim:

1. In a textile article treating apparatus in combination, a chamber having a door, an operator controlled member, means thrown into operation automatically upon operation of said member for closing said door, means acting automatically after the closing of said door for supplying a pressure heating medium to the interior of said chamber, means acting automatically for limiting the time of action of said heating medium, automatic power means for opening said door, and means arranged to act only after the pressure of the heating medium has dropped to a predetermined point to supply power to said door opening means.

2. In a textile treating apparatus in combination, a chamber having a door, means for supplying a textile treating heating medium under pressure to said chamber at times when said door is closed, a fluid operated power means for opening and closing said door, and means controlling the operating fluid for said power means including a normally open electric circuit, an operator controlled element adapted to close said circuit and a pressure operated switch for preventing opening of said door unless the pressure in the chamber is below a predetermined point.

3. In a textile article treating chamber apparatus, in combination, a chamber having a door, fluid operated power means for opening and closing said door, fluid operated power means for locking and unlocking said door, means for supplying a textile treating heating medium under pressure to said chamber, and means for controlling the fluid for both said fluid operated power means including electro-magnetically operated valves whose operating coils are included in circuits controlled in turn by a circuit having an operator controlled circuit closing element therein normally biased to the open position and a pressure operated switch for preventing opening of said door unless the pressure in the chamber is below a predetermined point.

4. In textile article treating apparatus in combination, a chamber having a door, a control member the position of which may be altered at will by an operator whenever said member is in an initial or neutral position, means thrown into action by placing said control member in a given position for closing the door of said chamber and for supplying heat to the chamber, means operating when said member is in said neutral position to turn off the heat to said chamber, and means preventing the operator from turning off the heat to the chamber for a definite period after it has been turned on.

5. In a textile article treating apparatus in combination, a chamber having a door, means for automatically closing and locking said door, means for automatically turning steam into said chamber, means for automatically turning off said steam and reducing the pressure thereof in said chamber, and automatic means to unlock

said door but only after the steam pressure has dropped to a certain point.

6. In a textile article treating apparatus in combination, a chamber having a door, means for admitting a heating medium to and exhausting it from said chamber, means to automatically close and lock the door, means for automatically unlocking and opening said door, and pressure responsive means for preventing the unlocking action of said last means unless the pressure in said chamber is below a certain point.

7. In a textile article treating apparatus in combination, a chamber having a door, a double acting fluid operated motor for closing and opening said door, a lock on said door, a double acting fluid operated motor for operating said lock, valves arranged to control the flow of operating fluids to said motors, electrical means including operating circuits for opening said valves, and a pressure operated switch in the circuit controlling said locking motor for preventing it from opening the lock unless the pressure in said chamber is below a predetermined point.

8. In a textile article treating apparatus in combination, a chamber having a door, means for locking and unlocking said door, means for turning pressure heating medium into said chamber and for turning it off therefrom, means for preventing the action of said means for turning on said heating medium unless the door is locked, and means for preventing the unlocking of said door unless the pressure in the chamber is below a given point.

9. In an apparatus for carrying out a cycle of operations initiated at the will of an operator, the combination of an operator controlled switch normally biased open, an electro-magnetic master switch having a plurality of contacts therein adapted to be thrown into either of two groupings, a coil in said master switch in circuit with said first switch whereby the coil is energized upon the closing of said first switch to throw said contacts into one grouping, circuit and switch means and mechanical means controlled thereby adapted when said contacts are in said one grouping to perform several mechanical operations one after the other in a given sequence, and automatic means adapted to throw said contacts into another grouping after said sequence of operations has been performed, said circuit, switch and mechanical means adapted when said contacts are in said other grouping to return the operated parts to their original positions by operations occurring in reverse sequence from said first operations.

10. In an apparatus for carrying out a cycle of operations initiated at the will of an operator, the combination as set forth in claim 9 and in which the means adapted to throw the contacts into another grouping is also adapted to produce a predetermined time interval between certain of the mechanical operations carried out by the apparatus.

11. In an apparatus for carrying out a cycle of operations initiated at the will of an operator, the combination as set forth in claim 9 and in which the apparatus includes a chamber and means for turning steam into said chamber while it is closed, and in which the means adapted to throw the contacts into another grouping is also adapted to produce a predetermined time interval between turning the steam into the chamber and regrouping the contacts but beginning only after steam pressure in the chamber has reached a given pressure.

12. In a textile article treating apparatus in combination, a chamber having a door, an operator controlled member, means thrown into operation automatically upon operation of said member for closing said door, means acting automatically after the closing of the door for locking the door, means acting automatically after the locking of said door for supplying a heating medium under pressure to the interior of said chamber, means acting automatically for limiting the time of action of said heating medium, automatic means for unlocking said door arranged to act only after the pressure in the chamber has dropped to a predetermined point, and automatic means for opening said door after it has been unlocked.

13. In a textile article treating apparatus in combination, a chamber having a door, and means for locking and unlocking said door comprising circuits including a mercury switch having two pair of contacts, and means whereby pressure in said chamber throws said mercury switch into position such that said locking and unlocking means is held positively in the locking position and whereby a subsequent lack of pressure in said chamber throws said mercury switch into position such that said locking and unlocking means is held positively in the unlocking position.

14. In a textile article treating apparatus, the combination as set forth in claim 13 and in which the locking and unlocking means includes a switch additional to the mercury switch and having an actuating coil deenergized when said mercury switch is in the position assumed by it when there is no pressure in the chamber and having contacts whereby a circuit is closed when the switch coil is deenergized for holding the locking and unlocking means positively in unlocking position.

15. In a textile article treating apparatus in combination, a chamber having a door, means for opening and closing said door, means for turning pressure heating medium into said chamber and for turning it off therefrom, means for preventing the action of said means for turning on said heating medium unless the door is closed, and means for preventing the opening of said door unless the pressure in the chamber is below a given point.

16. In a textile article treating apparatus in combination, a chamber, means for opening and closing said chamber, means for turning pressure heating medium into said chamber and for turning it off therefrom, means for preventing the action of said means for turning on said heating medium unless the chamber is closed, and means for preventing the opening of said chamber unless the pressure therein is below a given point.

17. In a chamber apparatus for treating textile material, in combination, a chamber having an opening for loading and a closure therefor, motor means for opening and closing said closure, locking means for said closure, motor means for moving said locking means into position to hold said closure closed or to release it for opening, and control means for said second mentioned motor means including electrical switches and circuits and a timing means acting to throw said switches and circuits into positions permitting said second mentioned motor means to move said locking means into release position, and a pressure controlled switch in said circuits and arranged to prevent said second

mentioned motor means from initiating a releasing movement of said locking means unless the pressure in said chamber is below a certain point.

18. In a textile treating apparatus in combination, a chamber having an opening for loading and a closure therefor, power means arranged to close said closure, to lock said closure, to turn a pressure medium into said chamber, to turn off said medium from said chamber and to unlock and open said closure, electrical control circuits for said power means, means for controlling said circuits arranged to time the period said medium is turned into said chamber, said circuits including a switch held in a certain position so long as the pressure in said chamber is above a given point and acting when open to prevent said power means from unlocking said closure.

19. In a textile article treating apparatus in combination, a chamber having an opening and a closure therefor, and means for locking and unlocking said closure comprising circuits including a switch having two active positions, and means whereby pressure in said chamber throws said switch into one of said active positions in which said locking and unlocking means is held positively in the locking position and whereby a subsequent lack of pressure in said chamber throws said switch into the other of said active positions in which said locking and unlocking means is held positively in the unlocking position.

20. In a textile article treating apparatus in combination, a chamber having an opening and a closure therefor, a control member the position of which may be altered at will by an operator whenever said member is in an initial or neutral position, means thrown into action by placing said control member in a given position for closing said closure and for supplying a pressure heating medium to the chamber, means operating when said member is in said neutral

position to turn off the heat to said chamber, means preventing the operator from turning off the heating medium from the chamber for a definite period after it has been turned on, means 5 acting after said heating medium has been turned off to open said closure, and means preventing the start of the opening movement of said closure until after the pressure in the chamber has fallen below a certain point.

21. In a textile article treating apparatus in combination, a chamber having an opening and a closure therefor, an operator controlled member, means thrown into operation automatically upon operation of said member for closing said closure, means acting automatically after the closing of the closure for locking the closure, means acting automatically after the locking of said closure for supplying a heating medium under pressure to the interior of said chamber, 20 means acting automatically for limiting the time of action of said heating medium and adapted to prevent the operator from curtailing the time of a given run of the heating medium when once begun, automatic means for unlocking said closure arranged to act only after the pressure in the chamber has dropped to a predetermined point, and automatic means for opening said closure after it has been unlocked.

22. In a pressure treating apparatus in combination, a chamber having a door, power means for locking and unlocking said door, means for turning pressure heating medium into said chamber and for turning it off therefrom, means for preventing the action of said means for turning on said heating medium unless the door is locked, and means for preventing the supply of power to said locking and unlocking means for unlocking said door unless the pressure in the chamber is below a given point.

CHRISTIAN F. MEYER.
